HERMAN G. BENDIX, OF NEW YORK, N. Y.

HEEL-BREAST BUFFER.

1,073,949.

Specification of Letters Patent. Patented Sept. 23, 1913.

Application filed January 14, 1913. Serial No. 741,921.

To all whom it may concern:

Be it known that I, HERMAN G. BENDIX, a citizen of the United States, and a resident of the city of New York, borough of Brooklyn, in the county of Kings and State of New York, have invented a new and Improved Heel-Breast Buffer, of which the following is a full, clear, and exact description.

10 This invention relates to shoe machinery, and has particular reference to tools for operating upon shoes and particularly the heel breasts of the finer grades of shoes.

Among the objects of this invention is to 15 improve heel breast buffers so that the buffing operation may be performed in a better and more rapid manner than has heretofore been possible and also whereby the danger of damaging the texture or finish of the fine 20 material of which the main portion of the shoe or slipper is constructed may be obviated.

A further object of the invention is to 25 provide a buffer which may be maintained in a satisfactory operative condition for rapid work at a low cost and which is adapted to operate upon different portions of the heel.

The foregoing and other objects of the 30 invention will hereinafter be more fully described and claimed and illustrated in the drawings forming a part of this specification in which like characters of reference indicate corresponding parts in all the views, 35 and in which—

Figure 1 is a perspective view indicating the manner of using the tool in one position; Fig. 2 is a side elevation of the buffer and longitudinal section of the chuck for 40 operating it; Fig. 3 is a blank showing the manner of cutting the material for forming the abrading sheath; Fig. 4 is a perspective view of the sheath as it is made and ready to be applied to the buffer; and Fig. 5 is a 45 longitudinal section of the buffer complete.

Referring more particularly to the drawings, I show at 10 a buffer of a substantially cylindrical form and adapted to be rotated at high speed by means of a flexible shaft 11 50 driven from any suitable motor. The buffer comprises a shank 12 fitted into a chuck 13 to the end 14 of which said shaft may be connected in any suitable manner. The buffer through the shank is adapted to be held by the operator substantially as indicated in Fig. 1, the handle including a

sleeve 15 which surrounds the chuck. The material of the sleeve is preferably of felt or some other absorbent material whereby any oil which may exude from the chuck 60 will be caught thereby and prevented from spattering the shoe. Said chuck preferably includes an outwardly and rearwardly projecting flange 16 which directs said oil away from the shoe. The shank 12 of the buffer 65 may be secured in the chuck for rotation therewith by any suitable means.

The body of the buffer comprises a core 17 fitted to the end of the shank opposite the chuck and surrounding the core is a cylindrical body 18 of rubber or other suitable flexible and resilient material. The body is preferably connected to the core by cement or other suitable permanent means, but the core is adapted to be slipped on or off the shank freely. The abrading sheath 19 is preferably formed in the manner indicated in Figs. 3 and 4, and comprises a cylindrical member formed from comparatively light and cheap carborundum or other suitable abrading paper. The blank employed to form the sheath is cut as shown in Fig. 3, having a substantially rectangular body portion 19^a which, when rolled upon itself and glued along the line 19^b, will form the cylinder of the sheath. The blank also shows the fastening tabs 19^c which are adapted to be bent substantially at right angles, one of said tabs spanning each end of the sheath. The sheaths made as indicated may be produced and sold to the trade in large quantities at low cost. The sheath is applied to the buffer by slipping it over the body 18 and then passing the end 12' of the shank through one of the tabs 19^a and 90 the core 17 and finally through the tab 19^c at the opposite end. A nut 20 may then be screwed upon the end 12' binding the buffer in place upon the shank and against a shoulder 21 formed thereon. The tabs therefore 100 will provide an effective means for securing the sheath for rotation or displacement with respect to the main portions of the buffer during ordinary operation.

As illustrated in Fig. 1, the buffer may be 105 used to advantage in dressing out the heel breast 23 which is curved longitudinally and transversely of the shoe. The buffer extending transversely of the shoe and operated at a high speed will quickly and effectively treat this portion of the shoe, a sufficient rolling movement of the buffer in a 110

plane transverse to the shoe being given to it for the purpose of conforming to the transverse curvature without any danger of abrading or damaging the texture of the 5 satin or fine leather constituting the face of the shoe. Another use for the buffer is to finish the lower front portion 24 of the heel which also is concave in this character of shoe. For this purpose the shoe and buffer 10 will be differently positioned from that shown in Fig. 1, the axis of the shank 12 of the buffer lying in substantially the vertical longitudinal plane of the shoe. The dust resulting from the abrading action of the 15 buffer will not adhere to the sheath and clog up the same under ordinary conditions because of the elasticity and vibration given to the sheath by virtue of the body 18 of the buffer. By this fact the life of the sheath 20 is very much increased. When, however, the sheath becomes worn and unfit for use, it may easily be removed, reversing the process already described, and a new sheath applied in its place.

25 Having thus described my invention, I claim as new and desire to secure by Letters Patent:

1. In an abrading device, the combination of a shank having a shoulder intermediate

its ends, a core surrounding one end of the 30 shank, a resilient body of cylindrical form surrounding and secured to said core, a sheath of abrading material removably fitted around said body, said sheath including a tab at one end, and means to secure the 35 core, body and sheath removably to the shank, said tab being gripped between said shoulder and the core.

2. In an abrading device, the combination 40 of a shank, a core slidably fitted upon said shank, a sheath of abrading material of hollow cylindrical form surrounding said core, said sheath including an integral tab at each end, each tab having a hole therethrough and bent up across the end of the 45 cylindrical portion, the shank aforesaid being slipped through said holes in the tabs, and means securing the core and sheath removably to said shank, said securing means serving to grip both of said tabs squarely 50 against the ends of the core.

In testimony whereof I have signed my name to this specification in the presence of two subscribing witnesses.

HERMAN G. BENDIX.
